UNITED STATES PATENT OFFICE.

SAMUEL S. STOLP, OF MANSFIELD, OHIO, ASSIGNOR TO THE OHIO BRASS COMPANY, OF MANSFIELD, OHIO, A CORPORATION OF NEW JERSEY.

ELECTRICALLY-OPERATED TRACK SWITCH.

Application filed December 20, 1923. Serial No. 681,678.

To all whom it may concern:

Be it known that I, SAMUEL S. STOLP, a citizen of the United States of America, residing at Mansfield, in the county of Richland and State of Ohio, have invented certain new and useful Improvements in an Electrically-Operated Track Switch, of which the following is a specification.

My invention relates to electrically and automatically operated track switches.

One object of my invention is to provide a system working under the well known principle of "power on" or "power off" the motors of the car.

Another object of my invention is to protect the track switch operating mechanism from a too long application of the operating current which, if applied too long, would have a tendency to injure the operating mechanism.

Another object of my invention is to provide a system to prevent the operation of the system by a car following the first car until the first car has passed over a predetermined distance beyond the switch point.

My invention resides in the new and novel construction, combination and arrangement of the various parts herein shown in the accompanying drawings and later fully described.

In the drawing accompanying this specification:

Fig. 1 is a schematic view showing the arrangement of the various car circuits which I take into account in designing the system.

Fig. 2 is a schematic view showing the arrangement of the various parts arranged for operating as set forth in the above objects.

Fig. 3 shows a modification of Fig. 2 in that by throwing a hand operated switch the system can be arranged so as to give no protection to the first car setting the system in operation against a following car, as is sometimes desired by the trade.

Referring to Fig. 1 I show a current collector or trolley wheel W mounted on a car by means of the trolley pole T. From the trolley pole to the ground extend several circuits including therein heaters H, lights L and air compressor F. Another circuit leading from the trolley pole to the ground comprises therein the motors M for operating the car and a controller C by means of which the operator can control the operation of the motors M.

My system is arranged such that if the operator desires to have his car moved "straight ahead" when he reaches a switching point, he will throw his controller to "power off" position on approaching the switch, and if he desires to take the "curve" he will throw his controller to the "power on" position. This latter will permit a heavy current to flow from the current collector through the motors and this fact I take into account in operating the system.

The current flowing through the apparatus H, L and F is independent of the controller C and as this may amount to considerable as compared with the current flowing through the motors M, I must take this fact into account in designing the system, as later explained.

In Fig. 2 the arrangement of the system is as follows:

I employ a contact pan P which is mounted in juxtaposition to the trolley conductor 1 and comprises two contact members 2 and 3 which are normally insulated from each other and adapted to be bridged or electrically connected by the current collector when engaged by the collector. The collector being of metal, the member 3 will be electrically connected to the contact member 2 when the collector engages the pan at the same time the collector will be out of engagement with the trolley conductor 1 due to the relative arrangement of the conductor 1 and the members 2 and 3. The member 3 is normally insulated from the trolley conductor.

I also employ an electrically operated switch A which is provided with an operating coil 4 usually composed of a comparatively few turns of very heavy wire sufficient to carry the current safely which flows through the motors M and the number of turns which I employ is so gauged that the current flowing through the apparatus H, L and F will not produce sufficient ampere turns in the coil 4 to pick up the switch arm 5, but when the collector engages the pan P with "power on" the motors the heavy current flowing through the coil 4 will produce sufficient ampere turns to pick up the arm 5. The terminals of the coil 4 are connected to the trolley conductor 1 and to the contact member 2 by the conductors 4' and 4" respectively thereby normally maintaining an electric connection between

the contact member 2 and the conductor 1. When the current collector engages the pan P with the controller turned to the "power on" position then the current will flow through the coil 4 and through the collector W to the contact member 3 and it will also flow through the pole T, the controller C, the motors M to ground thereby energizing the coil 4 and picking up the arm 5.

10 I also employ an electrically operated track switch S comprising solenoids 6 and 7, a plunger 8, a switch tongue 9 and a connecting member 10. One terminal of each solenoid is connected to the ground G through the common conductor 11. When the solenoid 6 is energized the plunger 8 will be drawn inwardly and the switch tongue 9 moved to the "straight ahead" position and the solenoid 6 will be energized, as later explained, whenever the collector engages the pan P with "power off". Whenever the solenoid 7 is energized the plunger 8 will be drawn outwardly thereby moving the switch tongue 9 to the "curve" position which is shown in Fig. 2. The solenoid 7 will be energized whenever the collector engages the pan with "power on" the motors.

15 The switch A is provided with two contacts 12 and 13. The arm 5 is normally in engagement with the contact 13, which in turn is connected to the remaining terminal of the solenoid 6 by the conductor 14. The switch A is also provided with a coil 15 in which the number of turns are so proportioned that the current flowing therethrough will not produce sufficient ampere turns to raise the arm 5, but which will be sufficient to hold the arm 5 in engagement with the contact 12 after the arm has been moved by 20 the energizing of the coil 4, and the coil 15 will hold the arm in engagement with the contact 12 as long as current is supplied to the arm 5, as later explained. One terminal of the coil 15 is connected to the contact 12 by the conductor 16 and the other terminal is connected to the remaining terminal of the solenoid 7 by the conductor 17.

25 I also employ a switch B provided with a coil 18 and an arm 19. One terminal of the coil 18 is connected to the contact member 3 by the conductor 20. The other terminal has a ground connection G through the conductors 21, 22, 23 and coil 24 of the switch C. The windings on the coils 18 and 24 are of high resistance and many turns so as to permit only a small energizing current to flow therethrough. These coils are energized whenever the collector engages the pan P with either "power on" or "power off". The switch C is also provided with an arm 25, contact 26 and a coil 27. The coil 27 is provided with the same resistance and number of turns as the coil 24 and it has one terminal connected to the ground through the conductor 23 and the other ter-

30 minal connected to a pan P' through the conductor 28. The pan P' is provided with two contact members 29 to which the conductor 28 connects and conductor 30 which is normally connected to the trolley conductor 1 70 through the conductor 31. The function of the coil 27 and its connections and the pan P' will be later explained.

35 The switch B is provided with a contact 32 which is connected to the conductor 1 75 through the conductor 33. The arm 19 is connected to the arm 5 through the conductor 34. Whenever the collector engages the pan with "power on" or "power off" the coils 18 and 24 will be energized and their respective arms will be raised into engagement with their respective contacts. As soon as the arm 19 is raised current will flow from the conductor 1 to the arm 5 and from there to the solenoid 6 or 8, depending 80 whether the collector engages the pan with "power on" or "power off". If the collector engages the pan with "power off" the arm 5 will remain in engagement with the contact 13 and the solenoid 6 will be energized thereby moving the switch tongue 9 to the "straight ahead" position. On the other hand, if the collector engages the pan P with "power on" the coil 4 will be energized, the arm 5 raised into engagement with the contact 12 and the coil 15 and solenoid 7 will be energized, moving the switch tongue to the "straight ahead" position. At the same time the energizing of the coil 15 will hold the arm 5 in engagement with the contact 12 as long as current is flowing through the solenoid 7 and this duration of time will depend upon the duration of time that the arm 19 engages the contact 32. In order to protect the coil 6 from too long an application of current I provide means through the operation of the switch C to cause the switch B to open after it has been closed for a pre-determined time. If the collector passes across the pan P without stopping with 100 either "power on" or "power off" the duration of time of the application of current to the track switch operating mechanism will not be sufficiently long to injure the same, but if the collector should come to rest in contact with the pan the duration of time might be sufficient to cause the operating track switch mechanism to be injured and hence I employ the switch B for 105 protecting the mechanism.

110 As soon as the coil 24 is energized the arm 25 is brought into engagement with the contact 26 and as the contact 26 is connected to the conductor 21 by the conductor 35 and the arm 25 is connected to the trolley wire 115 through the conductors 33, 36 and 37 and the hand operated switch 38, it will be evident that when the switch C is closed I am virtually short circuiting the coil 18 as the conductor 20 is then in connection with the 120 125 130

trolley conductor 1 and the conductor 21 is also in connection with the trolley conductor 1. This short circuiting of the coil 18 will deprive it of its current and in time 5 the arm 19 will drop thereby opening the circuit leading to the switch arm 5 and depriving the track switch operating mechanism of current. When the arm 25 engages the contact 26 in addition to short circuiting the coil 18 the coil 24 will be supplied with current directly from the conductor 33 which connects to the trolley conductor and, therefore, the coil 24 will be continuously energized and as long as it is energized 10 the arm 25 will be raised and the coil 18 short circuited and the switch B remain open.

It will be evident that having once closed the switch C that the system cannot again 20 be operated regardless of the number of cars which may engage the contact pan P until the switch C has been opened and, therefore, I must provide means for opening the switch C after the switch C has been closed by a car setting the system in operation. To do this, I make use of the coil 27, 25 already described, and it will be evident that when a collector engages the pan P' that current is then free to flow through the coil 27 to ground and as this is equally energized with that of coil 24, and as I connect these coils for differential operation, the holding effect of the coil 24 will be destroyed 30 and the arm 25 will drop and the system returned to normal.

The pan P is usually placed on the approach side of the track switch and the pan P' at a distance beyond the track switch to have safely passed the switch before the 40 system is returned to normal.

The switches A, B and C are each provided with a magnetizable core, either fixed or movable, as is well known in the art, and the switch B is provided with a delayed 45 release in opening which may be secured by the use of a dash-pot, a copper or brass sleeve about the core or coil 18, or by proper relation of the arm 19 to the core as regards the air gap, or other well known 50 means may be employed for securing a delayed release thereby permitting current to flow through the contact switch operating mechanism for a sufficient time to fully saturate its coils.

55 It will be evident that if the car stands with its collector in contact with the pan P for a time greater than the time factor of the switch B that the switch B will open and when the car starts forward due to the operator applying current to the motors, that while the arm 5 may be moved into engagement with the contact 12 that the track switch will not be changed on account of the switch B being open.

60 It will be evident that I maintain the switch inoperative by maintaining the switch C closed thereby preventing operation of the switch B while the switch C is closed and through this operation I protect the system from being changed from its 70 initial operation by the car setting the system in operation while it is in cooperative relation with the system, and I also prevent the system from being changed by a car following the first car until the first car has 75 passed the track switch and reached a predetermined point distant. It is sometimes desirable to operate the system without the use of the pan P' and, therefore, the system must be arranged so that the switch C will 80 open after the car has passed the pan P and to do this I employ the double throw hand operated switch 38 which can also connect the conductor 20 with the conductor 37 through the conductor 39. When the switch 85 38 engages the conductor 39, as in Fig. 3, it will be noted that when the switch C is closed I still place a short circuit about the coil 18 thereby causing the switch B to open and that current for maintaining the 90 switch C closed is then drawn from the contact member 3 in place of from the trolley conductor 1. This arrangement will maintain the switch C closed as long as the current collector engages the pan P so that the 95 member 3 is energized, but as soon as the collector leaves the pan P no current can flow to the coil 24 to maintain its energization, and the arm 25 will open, returning the system to normal and ready for operation by a following car regardless of whether the car has passed the track switch or not, but this situation is usually taken care of by placing the pan P very closely to, but 100 in advance of the track switch.

105 Of course, if the system is to be used without the pan P' at all times, then there is no need of installing the pan P' and the coil 27 may be omitted and its connections and also the conductor 37 would be permanently connected to the conductor 39 or 20.

110 There are, of course, many modifications which may be made in the parts and circuits of my disclosure, but which modifications will still fall within the scope of my invention.

I claim:

115 1. A switch operating system comprising in combination, an electrically operated track switch, circuits and electrically operated means therefor to operate the track switch to the position desired, a control switch for first closing and then opening one of said circuits after a predetermined time 120 when the device is in use so that a current collector will first close said circuit and later open the same whereby the track switch is rendered operative during the time the said control switch is closed and means provided with an operating coil directly con- 125

trolled by the current collector to short circuit the electrically operated means to cause said control switch to open after a predetermined time and to prevent its being closed while a cooperating car is passing over a desired distance.

2. A switch operating system comprising in combination, an electrically operated track switch operable to different positions, 10 two contact pans, a directional switch having an operating coil connected to and controlled from one pan by the motorman on a moving vehicle when the collector thereon engages the pan, a branched circuit having the branches controlled by the directional switch for controlling the movement of the track switch, a control switch to open and close said branched circuit, an electrically operated switch to control the said control switch having an operating coil energized from one pan to close the switch and a coil energized from the other pan to neutralize the effect of the first coil to open the switch such that when the collector engages the 25 first pan the electrically operated switch will close and when the collector engages the other pan the said switch will open.

3. A switch operating system comprising in combination, an electrically operated track switch operable to different positions, 30 two contact pans, a directional switch having an operating coil connected to and controlled from one pan by the motorman on a moving vehicle when the collector thereon engages the pan, a branched circuit having the branches controlled by the directional switch for controlling the movement of the track switch, an electrically operated switch provided with two operating coils to be energized in opposition to each other, circuits connecting said pans and electrically operated switch such that when the collector engages the one pan the electrically operated switch will be closed by energizing one of the 40 coils and held closed thereby and when the collector engages the other pan the said switch will open by energizing the other coil

and neutralizing the effect of the first coil to render the track switch inoperative between said engagements.

4. A switch operating system comprising in combination, an electrically operated track switch, a directional switch to control circuits leading to the track switch to position the track switch as desired, an electrically operated control switch to further control the currents to the track switch, an electric switch having two operating coils, a contact pan and circuits so arranged that a current collector engaging the pan will close 60 and maintain closed the electric switch by energizing one coil, another pan and circuits so arranged that a current collector engaging the pan will open the electric switch by energizing the other coil in differential 65 to the first coil to render the track switch inoperative between said engagements.

5. A switch operating system comprising in combination, an electrically operated track switch, a directional controlling switch, 70 an electrically operated control switch provided with an operating coil to control an operating circuit to said directional switch, two contact pans, an electrically operated control switch provided with two operating 75 coils, a circuit connecting the operating coil on the first said control switch and one of the operating coils on the last said control switch in series to energize said coils, and which in turn derive current from one of the 80 contact pans, other circuits connecting said elements so that a current collector engaging one pan will close said electrically operated control switches and the first said control switch will be shunted out and maintain 85 shunted while the current collector engages said pan and thereafter and the current collector will cause the second said control switch to open when it engages the second pan by energizing the second coil on said 90 second control switch.

In testimony whereof I affix my signature.

SAMUEL S. STOLP
